Max. Orduna

UNITED STATES PATENT OFFICE.

JOSEF SCHOLZ, OF SCHENECTADY, NEW YORK.

CIGARETTE-CASE.

1,218,705.

Specification of Letters Patent. Patented Mar. 13, 1917.

Application filed May 26, 1916. Serial No. 99,923.

To all whom it may concern:

Be it known that I, JOSEF SCHOLZ, a subject of the Emperor of Austria-Hungary, residing at Schenectady, in the county of 5 Schenectady and State of New York, have invented certain new and useful Improvements in Cigarette-Cases, of which the following is a specification.

The object of this invention is to provide 10 a case for cigarettes, cigars or similar articles, with a delivery opening and a delivery mechanism, which will allow the discharge of a cigarette of the like through said opening without opening the case.

15 With this object in view, my invention consists in the construction, arrangement and combination of parts, as will be herein-after fully described and set forth in the appended claims.

20 In the drawing, which forms part of this specification and in which similar reference characters denote corresponding parts, Figure 1 is an elevation of my new case when closed; Fig. 2 is an elevation thereof when 25 open; Fig. 3 is a vertical section on line 3—3 of Fig. 1; Fig. 4 is a vertical section on line 4—4 of Fig. 1 and Fig. 5 is a cross section on line 5—5 of Fig. 2.

Referring specifically to the drawing, *a*, *b* 30 denote the receptacle and lid respectively, of my case, the lid being hinged or otherwise pivotally secured to the case at *b'* and *b''* and provided with the usual lock or snap *b'*.

35 The receptacle *a* is made wider than the length of the article stored therein and is provided near its inner side with a longitudinally extending wall or partition *a'* which divides the interior thereof into two compartments, the wider compartment serving 40 to receive a number of cigarettes or similar articles *c* which are stored therein transversely in a longitudinal row, and the narrower compartment serving to contain the 45 means for operating the delivery mechanism which will be presently described.

At the upper end the receptacle is provided with a delivery opening *a'* extending 50 transversely throughout the width of the case and has a flap or wing *d* hinged or otherwise pivotally secured thereto and which serves to normally close the said opening. Below the latter the delivery mechanism, according to one embodiment of my

invention, consists of an angular bar *e*, *f*. 55 This bar extends transversely through the receptacle and is hinged or otherwise pivotally secured to the bottom thereof, as at *e'*, so as to be capable of swinging around a horizontal axis. Normally the member *e*, *f* 60 occupies such a position that the part *e* thereof rests substantially flatly on or adjacent and parallel to the bottom of the case, while the part *f* thereof projects substantially perpendicularly to the bottom, serving 65 to confine the articles within the space below it. The part *e* serves to lift the article which happens to lie on it and to present it in front of the delivery opening *a'*. This function is accomplished by swinging the member *e* upwardly from the bottom. In order to prevent the articles from rolling underneath the lifted part *e*, one or more coils *g* 70 may be arranged between the part *e* and the bottom of the case. 75

The means for operating the delivery mechanism simultaneously with the flap or wing *d* may consist of a short arm *h* pivotally connected to said parts, as at *h'* and *h''*, and a longer arm or bar *i* pivotally connected to the flap *d*, at *i'*, and to a pusher pin *j*, as at *i''*. This bar extends through the narrower compartment of the case, and the pusher pin is slidably borne in cross pieces *a'*, *a''* of the receptacle *a*. The pin *j* is actuated by a spring *k* connected to the same and contained in the space between the two cross pieces *a'*, *a''*. The outwardly projecting part of the pin is provided with a head *j'*. In order to allow for the pusher pin 80 being easily manipulated with the finger, the parts of the receptacle and that of the lid surrounding the outwardly projecting part of the pusher pin, are cut away, as at *a'* and *b'*. 90

In use the case is held in one hand with the index finger pressing on the head *j'* of the pusher pin and is tilted with its delivery opening downwardly, so that the articles in the case will roll toward the part *f* of the 100 delivery member and one of them will be deposited on the part *e*. By the depression of the pin the flap *d* will be flung open while simultaneously the article on the member *e* will be lifted and fall through the opening 105 into the user's other hand held below the opening.

As the construction may be easily modified

without departing from the spirit of my invention, I do not wish to restrict myself to the details described and shown.

What I claim and desire to secure by Letters Patent is:

1. A case for cigars, cigarettes, or other articles having a delivery opening, a delivery member pivotally secured in said case and including a part normally extending adjacent and parallel to the bottom of the case and spring members below said delivery member and on which the latter normally rests for preventing the articles from rolling underneath said part when the latter is tilted into delivering position.
2. A case for cigars, cigarettes, or other articles consisting of a receptacle having a delivery opening and divided into two compartments of which one serves to receive the articles, a delivery member in the first compartment including a part normally extending adjacent and parallel to the bottom of said receptacle, spring members below said delivery member and on which the latter normally rests for preventing articles from rolling underneath said part when the latter is tilted into the delivering position, a spring actuated push member and other means in the second compartment, said other means being pivotally connected to said push member and serving for positively operating said delivery member.
3. A case for cigars, cigarettes, or other articles comprising a receptacle having a delivery opening and divided into two compartments, of which one serves to receive the articles, a pivoted flap for said delivery

opening, a delivery member in one of the compartments of which one part is adapted to normally extend adjacent and parallel to the bottom of said receptacle, means for preventing articles from rolling under said part when the latter is tilted into the delivering position, a spring actuated push member and other means in the other compartment, said other means being pivotally connected to said push member and serving for positively and simultaneously operating the said flap and the delivery member.

4. A case for cigars, cigarettes, or other articles comprising a receptacle having a hinged cover and divided into two compartments one of which serves to contain the articles, a flap pivotally secured to one end of said receptacle, an angular delivery member extending transversely through said article-containing compartment and of which one part normally extends adjacent and parallel to the bottom of said compartment, spring members between said part and said bottom to hold the articles from rolling underneath said part when the latter is tilted into delivering position, a spring actuated push member and levers in the other compartment, said levers being pivotally connected to said push member and operatively connected with said flap and said member and allowing the simultaneous operation thereof.

In testimony whereof I affix my signature in presence of two witnesses.

JOSEF SCHOLZ.
